UNITED STATES PATENT OFFICE.

GEORGE COLVIN KENNEDY, OF WATERLOO, IOWA.

GAME APPARATUS.

Application filed March 25, 1925. Serial No. 18,216.

To all whom it may concern:

Be it known that I, GEORGE COLVIN KENNEDY, citizen of the United States, residing at Waterloo, in the county of Blackhawk and State of Iowa, have invented certain new and useful Improvements in Game Apparatus, of which the following is a specification.

My invention relates to improvements in game apparatus, and the object of my improvements is to supply an apparatus having relatively movable members which may be employed in different combinations and arrangements for fortuitously indicating and disclosing various plays and insignia relating thereto in a plurality of games, under different regulations devised therefor.

This object I have accomplished by the means which are hereinafter described and claimed, and which are illustrated in the accompanying drawings, it being understood that changes in the precise embodiment of invention herein disclosed can be made within the scope of what is claimed without departing from the spirit of the invention.

In said drawings:

Fig. 1 is a perspective view of my game apparatus as used, showing one sign-carrying flap indicated by indicating means and swung upwardly to disclose the insignia on its sign. Fig. 2 is a cross section of the apparatus of said Fig. 1, taken on the broken line 2-2 thereof. Fig. 3 is a perspective detail view of one of the removable flaps and its removable insignia carrying card. Fig. 4 is a plan of the inscribed back of one of the insignia cards. Fig. 5 is a plan view of one face of the subdivided insignia carrying indicating disk. Fig. 6 is a similar view of the opposite subdivided insignia carrying face of said disk.

The numeral 1 denotes a basal member, preferably shaped or stamped from a plate of metal rectangularly to have depending marginal supporting flanges. A pintle 14, being a headed and threaded bolt passed through an aperture 3 upwardly in the center of the member 1, serves as an axis on which is first mounted a round topped spacing apertured body 15, then above it a rotatable serrated disk 16, then another hollow spacing member 28, then a rotatable index 29, and finally a cap-nut 30.

The basal member 1 has a plurality of slotted apertures 2 arranged annularly and

concentrically about the axis pintle 14. A like plurality of hinged swinging flaps 4 are detachably hinged to the member 1 in the following manner. Referring to said Fig. 3, each flap 4 is shaped from plate metal with marginal opposite hooks 5 to removably seat a sign card or plate 6 upon its normally under face when lowered against the base 1. The wider lower margin of the flap 4 is cut and shaped with a medially spaced pair of finger-tabs 8 projecting at a right angle therefrom, and a medial reversely curved tab or hinge member 7 between the tabs 8 but projecting oppositely relative thereto. As shown in Fig. 2, the member 7 is passed through a slit 2 downwardly while erect. In this erect position the tabs 8 contact with the upper surface of the base 1 and serve as stops to prevent swinging outwardly of the flap beyond its erect position. When the flap is in its lowered position, as shown at the right hand part of the base 1 in Fig. 2, the tabs 8 serve as finger-pieces, for use in tilting the flap upwardly to its erected position and holding it until lowered again. The flap may be quickly and easily detached from the base 1, by erecting it and then drawing it upwardly and obliquely outwardly to separate from the slit 2. The flaps 4 are thus hinged upon said base concentrically around the pintle 14 to normally lie radially upon the base but having their tops spaced from the circumference of the serrated disk 16.

Each flap is a sign-carrying member, that is carries on its under face a sign having one or more insignia in subdivided compartments. These of course may be permanently displayed on the under face of the flap, but may also be placed upon one or the opposite surfaces of a sign-card or plate 6 which may be removably mounted within the flap hooks 5. The cards 6 may be readily removed at the wider lower ends of the flaps, after the flaps are disengaged from the base 1 when their hinge tabs 7 are disassembled from the slits 2, in order to reverse the cards in the hooked holders 5 to employ the insignia on the backs of said cards in certain games.

As the card 6 is shown in said Figs. 3 and 4 respectively with its front and back faces displayed, it will be seen that on both faces are compartments 11 with subdivision lines 13, each compartment containing an inscription or pictured insignia

which has a game relation to other inscriptions or insignia of a different kind shown in corresponding compartments 11 on all the other cards 6, or as also related to certain 5 insignia or inscriptions on one or other face of the disk 16, and as in either case indicated by the use of the rotatable index 29 fortuitously.

For an instance, a compartment 11 on the 10 card 6 as shown in Fig. 3 displays insignia 9, being a character represented in a series for a certain game, and also descriptive inscriptions or names and an inscribed numeral at 12, related thereto in the counting of the 15 game. On said card in other compartments 11 may be displayed playing card numerals and insignia at 10, also for other game purposes. The back of each card 6, as shown in Fig. 4 may bear other insignia 20 adapted for use in still other games.

Referring to Figs. 5 and 6, the opposite faces of the disk 16 are provided with different subdivided compartments carrying different characters, numerals or insignia.

25 For instance, the face shown in Fig. 5 has its serrated margin divided into compartments 17 carrying different numerals at 18, an inner concentric row of compartments 20 carry playing card suits at 21, while the 30 inner part of the surface is subdivided into quadrants 22 carrying suit signs 24. The opposite face of the disk shown in Fig. 6 has marginal compartments carrying single letters of the alphabet at 25. An inner concentric circle of compartments 26 carries 35 names of certain celestial bodies, while the inner part of the space is radially subdivided into compartments 27 having the different colors of the solar spectrum.

40 The rotary index 29 is used to fortuitously indicate either flap 4, only, as in successive plays in one game, or to at the same time cross and display some related compartment on one face of the disk 16, according to the 45 rules of another game.

The serrations of the disk 16 may also be used after rotating said disk to indicate one or more of the flaps 4, which latter when lifted disclose related but fortuitously selected compartments thereon. It is obvious that with this game apparatus many different games may be originated and played at the pleasure of the players.

50 Rules for twenty different games have been drawn up for use with this apparatus, and others could be added within the scope of the invention.

The following games will, however, disclose the use of the apparatus in playing 60 them.

Rainbow.

This game includes the use of the index 29, the disk 16 with its patterned face shown 65 in Fig. 7, and all the hinged flaps 4. In

turn the players rotate the disk, then rotate the index. The centrally arranged segments at 27 comprise all the colors of the spectrum, and the colors may have the following numerical values, viz: red, 7; orange, 70 6; yellow, 5; green, 4; blue, 3; indigo, 2, and violet, 1. The player adds the values of the two segments crossed by the oppositely directed parts of the index, then swings up 75 the flap 4 which is indicated by the index point, then adds to the other values the numeral whether plus or minus shown at 12 on the flap card 6. A minus numeral will be deducted from the sum of the disk numerals; and in case the flap card face is 80 that shown in Fig. 3, which is in its compartment 6 called the "Hoo Doo", the player loses the sum of the disk numerals and also secures a minus numeral on 6 to be deducted 85 from his previous total, if any. The player holding the highest plus total after six plays of each player, wins the game.

Jollity.

As shown in the middle compartment on 90 the flap card in Fig. 4, the name of a dance is given, such as "waltz". On the thirteen flap cards, different dance names are given, on the reverse. These may be the following, 95 dances: 1, Apache. 2, flirtation walk. 3, waltz; 4, two step; 5, polka; 6, one step; 7, tango; 8, fox trot; 9, jig; 10, highland fling; 11, hornpipe; 12, Indian dance, and 13, voodoo dance.

100 Each lady in turn rotates the disk using the face shown in Fig. 5. If the disk stops with a compartment numeral 18 crossed by the point end of index, she has a choice of gentleman partner in turn with the other ladies, for instance if she has the numeral 105 6, she has the sixth turn to select a partner. If there are more than thirteen couples, after the first thirteen couples have been 110 denominated, the operation is repeated. Then the lady of couple No. 1, rotates the 115 index, and swings up the flap 4, a card face as in Fig. 4 being displayed. If the dance name on this card is "waltz" then this couple waltz once around the room, then all the other couples also engage in waltzing. The lady No. 2 then selects a dance in the 120 same way, and so on in succession.

Cribbage, Junior.

120 Use the disk face shown in Fig. 5. Each player in turn rotates the index 29, and its point end will indicate a trump 24 on one of the red or black quadrants 22. The player then rotates the index again, and lifts up the 125 two flaps 4 indicated by the opposite ends of the index, using the cards shown in Fig. 3 and the suits as given on the lower compartments 11 thereof at 10. The counting 130 is the same as in the card game cribbage, and may be tallied in the same way on a

cribbage counting board or by pencil. Thus, pairs, sequences, fifteen twos, etc., are counted, and the player holding a knave of trumps also counts one for that. In case the player has on his two flap cards, not counting court cards, any combination of spots which added make 13, he loses thirteen points from his tally.

Having described my invention, what I claim as new, and desire to secure by Letters Patent, is:

1. In a game apparatus, a movable indicating device, and a plurality of movable sign-carrying flaps positioned within the scope of indicating movements of said device and each movable from a sign-disclosing to a sign concealing position.
2. In a game apparatus, a base, a movable indicating device mounted thereon, and a plurality of ranged sign-carrying flaps mounted detachably and swingingly upon said base within the scope of movements of said indicating device.
3. In a game apparatus, a base, a plurality of indicating devices mounted rotatably on a single axis on said base, and a plurality of swinging flaps mounted detachably upon said base independently within the scope of movements of the indicating devices.
4. In a game apparatus, a plurality of indicating devices mounted on a common axis for independent actuations, supporting means having apertured seats ranged within the scope of movements of said devices, and sign-carrying devices having basal hinge members shaped to detachably and interlocking engage with said apertured seats swingingly to swing from sign-concealing to sign-disclosing positions independently, the signs on said last-mentioned devices having independent insignia for fortuitous selection by said indicating devices.
5. In a game apparatus, a base member having an erect pintle fixed thereon, an indicating device rotatable on said pintle and having surface subdivisions containing insignia, another indicating device also rotat-

able on said pintle, and signs detachably hinged on said base member around said indicating devices, to be independently swung from sign-concealing to sign-disclosing positions, the insignia on the first-mentioned indicating device having fortuitous relations with the different signs.

6. In a game apparatus, a base member having a plurality of flaps detachably hinged thereto in a determined positional relation to each other, said flaps having seats for removably receiving insignia inscribed bodies, said bodies being inscribed on opposite faces and reversible in said seats, and indicating means mounted on said base member to fortuitously indicate either of said flaps, movably.

7. In a game apparatus, a tabular base member having hinge apertures, flaps having terminal hinge members shaped to enter said apertures interlockingly, detachably and swingingly, said flaps having terminal projections directed to one side for the manual swinging up of the flaps from a lowered position, and signs detachably mounted on said flaps having surface subdivisions containing different insignia, of which certain insignia on the flaps have a relation to a certain game, and means for fortuitously indicating any of said flaps while the latter are in sign concealing positions.

8. In a game apparatus, a tabular base member, flaps having hinge members hingedly connected to said base member, a pintle fixed on said base member spaced from said flaps, and independent indicating devices mounted rotatably on said pintle to be rocked to indicate either flap fortuitously, signs mounted on said flaps containing insignia, one of the indicating devices having surface subdivisions containing insignia, the other indicating device being a pointer, and the insignia on the first-mentioned indicating device having game relations respectively to certain insignia upon said flap signs.

In testimony whereof I affix my signature.

GEORGE COLVIN KENNEDY.
